UNITED STATES PATENT OFFICE.

CHARLES F. RITCHEL, OF BRIDGEPORT, CONNECTICUT, ASSIGNOR OF
ONE-HALF TO ALBERT T. FREE, OF NEW YORK, N. Y.

BOAT-PROPELLER.

SPECIFICATION forming part of Letters Patent No. 760,758, dated May 24, 1904.

Application filed October 17, 1903. Serial No. 177,385. (No model.)

To all whom it may concern:

Be it known that I, CHARLES F. RITCHEL, a citizen of the United States of America, and a resident of Bridgeport, county of Fairfield, 5 and State of Connecticut, have invented certain new and useful Improvements in Boat-Propellers, of which the following is a specification.

My invention relates to paddle mechanism for propelling boats; and it consists of an improved construction of manifold paddle gangs or clusters made to revolve each in its own circular orbit for dipping in and acting on the water and returning free of the water and means of so operating them, as hereinafter described, reference being made to the accompanying drawings, in which—

Figure 1 represents a cross-section of a boat with my improved propelling apparatus, representing one way in which it may be carried out in practice. Fig. 2 is a detail in longitudinal section on line 2 2 of Fig. 1. Fig. 3 is a perspective view of one of the paddle-gangs detached from the boat.

In this representation of my invention I show the paddles as applied in a fore-and-aft channel along the middle of the bottom of the boat.

A represents the shell or body of the boat, having a channel b of more or less length and 30 depth along the bottom and each side of the keel c, or it may be two separate channels, which is to be understood, although only hereinafter mentioned in the singular number, as intended to mean one or two channels, said 35 channel being open to the water below and being partitioned from the interior of the boat by an air-tight hood d, inclosing an upward extension-space r for the paddle apparatus.

Within the boat and on each side of the 40 channel a driving-engine e is located, which may of course be of any approved kind or construction, said engines being in alinement with each other as to their driving-shafts f, which range transversely of the boat and 45 which carry a crank or disk g respectively within the hooded space r, each having a wrist-pin h and extending into connection with a similar crank or disk i, carried on a short shaft j in a bearing k, centrally located between the

two engines and preferably carried on a support l, mounted on the keel c.

On the wrist-pin h a manifold paddle-header m is pivoted intermediately of its lengthwise extremities, which are similarly pivoted at n to wrist-pins carried by idler cranks or disks p to control the paddle-headers in respect to their circular movements, and these wrist-pins also connect with other coöperating idler cranks or disks p', thus affording support to both ends of the wrist-pins for substantial 60 construction and durable operation.

The headers m carry rigidly-attached downwardly-projecting paddles q in any suitable number, according to the length of the headers, and arranged at suitable intervals apart 65 to have propelling effect on the boat when moving backward—relatively to the movement of the boat—in the lower part of their course.

The paddles are beveled on the hind side to 70 reduce them to wedge shape for entering the water with least resistance, and it is to be noticed that this bevel of the hind side causes propelling effect on the paddles as they enter the water.

Two gangs or clusters of paddles will be used, placed in a channel and so coupled that they will act alternately in and out of the water, and thus operate with minimum shocks and jars. In this case this coupling is to be seen 80 by the connection of the crank-disks i, by the short shaft j, and the connection of the headers to opposite sides of the centers of the crank-disks, respectively.

The headers may of course be made in any 85 appropriate length and have any approved number of buckets.

It is to be seen that part of the channel where the paddles are located and geared is upwardly extended, as at r, before mentioned, 90 to provide space for the gears and without means to prevent would be flooded with water, which would to some extent hinder the proper working of the paddles. I have therefore provided the said air-tight hood d in 95 which to retain a supply of compressed air for controlling the level of the water and have connected said space by pipes s with the

compressed-air chambers *t* of the engines for supplying the air. Any suitable relief-valves may be employed to control the pressure of the air in the paddle-spaces. It is, however, 5 desirable for well-known reasons to locate the paddles under the boat and employ the compressed-air water-level controller,

What I claim as my invention is—

1. In boat-propelling apparatus, the combination of a paddle-header having one or more rigidly-attached paddles, a rotating driving crank or disk and wrist-pin connected thereto for operating said header, means for operating said crank or disk, and rotatory idler cranks or disks, and wrist-pin connections of the header therewith for controlling the header in respect of its rotatory motion.

2. In boat-propelling apparatus, the combination of a paddle-header having a series of 20 rigidly-attached paddles placed at intervals along its lengthwise, a rotating driving crank or disk and wrist-pin for operating the header, means for operating said crank or disk, and rotatory idler cranks or disks, and wrist-pin 25 connections of the header therewith for controlling the header in respect of its rotatory motion.

3. In boat-propelling apparatus, the combination of a paddle-header having one or more 30 rigidly-attached paddles, a rotatory driving crank or disk and wrist-pin for operating the header, means for operating said crank or

disk, rotatory idler cranks or disks, and wrist-pin connections of the header therewith for controlling the header in respect of its rotatory motion, a duplicate of the driving crank or disk and wrist-pin connection, and shaft carrying the same in the axial line of the driving crank or disk, and duplicate rotatory idler cranks or disks and wrist-pin connections with 35 the header in the axial lines of the first-mentioned idler cranks or disks, said header being carried intermediately of the respective driving and idler cranks or disks.

4. In boat-propelling apparatus, the combination of two paddle-headers each having one or more rigidly-attached paddles, a rotatory driving crank or disk and wrist-pin connections to each header for operating them, means for operating said cranks or disks, duplicate rotatory idler cranks or disks and wrist-pin connections of the headers therewith for controlling the headers respectively in respect to their rotatory motions, and means positively connecting the driving and idler 50 cranks of the respective headers for unity of action in alternating application of the driving power.

Signed at New York this 28th day of September, 1903.

CHARLES F. RITCHEL.
